UNITED STATES PATENT OFFICE

1,952,566

PROPELLER BLADE ADJUSTING SYSTEM.

Joseph J. Ring, Wauwatosa, Wis., assignor to
Allis-Chalmers Manufacturing Company, Mil-
waukee, Wis., a corporation of Delaware

Application October 5, 1932, Serial No. 636,263

8 Claims. (Cl. 253—148)

This invention relates in general to hydraulic energy translating devices of the adjustable blade propeller type, and more particularly to a propeller blade tilting servo-motor actuated by a 5 motor driven pump.

In hydro-electric generating units having adjustable propeller blades it has been proposed to tilt the blades during operation by means of reduction gearing and an electric motor carried by 10 the propeller shaft, however, in large units it is extremely difficult to provide reduction gearing strong enough to transmit the large forces necessary to tilt the blades and yet be sufficiently compact to be mounted within the propeller shaft or 15 a gear housing carried thereby.

It is, therefore, an object of the instant invention to provide a hydraulic energy translating system having a rugged, compact servo-motor which is actuated by a motor driven pump and is 20 carried by the propeller shaft.

Another object of this invention is to provide a system of the above character having electrical means for stopping the pump motor at the end of travel of the piston.

25 A further object of this invention is to provide a system of the above character having means for maintaining the servo-motor cylinder completely filled with operating fluid.

A still further object of this invention is to provide 30 a system of the above character having means for indicating the position of the propeller blades.

These and other objects and advantages are obtained by this invention, various novel features 35 of which will be apparent from the description and drawing herein, and will be more particularly pointed out in the claims.

An illustrative example of the application of 40 this invention is shown in the accompanying drawing in which:

Figure 1 is a side view of a hydro-electric generating unit partly in section embodying the instant invention;

Fig. 2 is an enlarged side view partly in section 45 of a portion of the apparatus shown in Fig. 1;

Fig. 3 is a sectional side view of the servo-motor cylinder taken 90° from the view shown in Fig. 2.

The hydraulic energy-translating device specifically illustrated in Fig. 1 comprises a generator 50 10 and a turbine 11 which are supported by a suitable foundation 12. A servo-motor 13 is interposed between propeller shaft 15 and generator shaft 14 and an electric pump motor 16 is mounted on the upper end of generator shaft 14 for rotation therewith.

Referring more particularly to Fig. 2, propeller hub 17 is provided with a plurality of blades 18 which are rotatably journaled in roller bearings 19. Each blade is provided at its inner end with a crank 21 keyed thereto. Each crank is connected to adjusting block 23 by means of a link member 22. Propeller hub 17 is attached to propeller shaft 15 by means of a flanged connection. Propeller shaft 15 is provided with an axial bore adapted to receive propeller blade adjusting shaft 24. For a more complete disclosure of one form of blade tilting mechanism which may be used with the present invention reference may be made to Patent No. 1,685,756 issued September 25, 1928, to J. J. Ring.

The upper end of propeller shaft 15 is provided with an enlarged portion 25 which constitutes a cylinder member for servo-motor 13, cylinder 25 is preferably attached to generator shaft 14 by means of a flanged connection and it is to be understood that this cylinder member may, if desired, also be attached to propeller shaft 15 in a similar manner. Blade tilting shaft 24 extends through a stuffing box 27 and is attached to piston member 26. A pump 28 preferably of the gear type is mounted on the upper face of piston 26 and in the embodiment illustrated in Fig. 3 comprises upper plate 29, middle plate 31 and lower plate 32 which are suitably bolted to piston 26. The above described plates define a chamber within which gears 33 and 34 are arranged. Pump 28 is provided with conduit 35 which is in communication with the space below piston 26 and is also provided with a conduit 36 which is in communication with the space above said piston. A pump shaft 37 is suitably attached to gear 34 and extends through stuffing box 38 in the lower end of generator shaft 14. The space between pump shaft 37 and generator shaft 14 constitutes a chamber 39 for the storage of operating fluid for servo-motor 13. Operating fluid may be introduced into chamber 39 by means of filler cap 42. A spring biased check valve 41 is arranged between storage chamber 39 and the upper chamber of servo-motor 13.

Pump motor 16 is attached to the upper end of generator shaft 14 by means of a tubular support 43. Motor support 43 is provided with one or more slots 44 through which indicator member 45 is adapted to slide, noting that the indicator member is carried by the upper end of pump shaft 37 by means of any suitable thrust bearing connection. A portion of support member 43 is provided with a number of marks which cooperate with member 45 as shown

.100

105

110

in Fig. 1, to indicate the position of the propeller blades during operation and at standstill. A drive shaft 46 is suitably connected to motor shaft 47 and is provided at its lower end with 5 a splined connection which permits shaft 46 to telescope within pump shaft 37 when piston member 26 is moved up and down.

A plurality of slip rings 48 are suitably mounted 10 on motor support 43 and are electrically connected to the windings of motor 16 which is preferably of the three-phase type. A plurality of brushes 49 are carried by stationary brush support 51 and contact with the respective slip rings 48. The windings of motor 16 may be 15 selectively connected to a suitable three-phase power line 52 through either switch 53 or 54. Push buttons 55 and 56 are provided for selectively energizing switches 53 and 54 from a suitable source of power 57. An overload relay 58 20 is provided with contacts in series with the source of power 57 and is energized from a current transformer 59.

The operation of the above described system 25 is as follows. If it is desired to flatten the tilt of propeller blades 18, push button 56 may be operated to its lower position to close switch 54. Pump motor 16 is thereupon caused to rotate in such a direction as to transfer operating fluid from the lower chamber of servo-motor 13 to 30 the upper chamber thereof thereby causing piston 26 to move upwardly. Upward movement of piston 26 is transmitted through rod 24, adjusting block 23, links 22 and to levers 21 thereby causing blades 18 to assume a more nearly horizontal position. If it is desired to increase the 35 tilt of the propeller blades, push button 55 may be operated to close switch 53 thereby causing motor 16 to rotate in an opposite direction. In a manner apparent from the above description 40 pump 28 will transfer operating fluid from the lower side of piston 26 to the upper side thereof, thereby causing blades 18 to assume a more nearly vertical position.

After propeller blades 18 have been moved to 45 the desired position as indicated by indicator member 45 and the indicia on member 43, motor 16 may be stopped by the operator removing his hand from the selected push button. If the operator holds either push button in its lowermost position until piston 26 moves to its uppermost or lowermost position, pump motor 16 will 50 become overloaded by reason of the continued operation of pump 28 thereby causing overload relay 58 to open thus stopping pump motor 16 by opening switch 54 or 53. Overload relay 58 55 is preferably of the type which must be reset by hand after it has moved to its open position. Obviously, limit switches of known type may be used to stop motor 16 at the limits of travel 60 of piston 26 instead of overload relay 58.

If the reaction of the water on blades 18 is such as to continually bias piston 26 downwardly it is possible that a small amount of oil may leak through stuffing box 27. However, this leakage is compensated by means of check valve 41 which opens by reason of the reduction in pressure thus caused in the upper chamber. Similarly any air that might possibly leak into the servo-motor cylinder may be discharged through check valve 41 and replaced with oil upon occurrence 70 of reduction of pressure in the upper chamber of the servo-motor.

It is to be understood that the above described embodiment of the invention is merely illustrative and that many changes in form, construc-

tion and arrangement of parts may be resorted to without departing from the principle of the invention defined by the appended claims.

It is claimed and desired to secure by Letters Patent:

1. In combination a generator having a rotatable vertical hollow shaft, a hydraulic turbine arranged below said generator and having a rotatable propeller with tiltable blades, blade tilting means operatively connected to said blades, a hollow propeller shaft attached to said propeller, a servo-motor cylinder interposed between said hollow generator shaft and said hollow propeller shaft, a piston within said servo-motor cylinder, a quantity of liquid within said cylinder, a propeller blade tilting rod extending from said piston through said hollow propeller shaft and operatively connected to said blade tilting means, a rotary pump mounted on said piston, the inlet and outlet of said pump being on opposite sides of said piston, a rotary motor mounted above said generator, and pump driving means connected between said pump and said motor. 80 90 95

2. In combination a generator having a rotatable vertical hollow shaft, a hydraulic turbine arranged below said generator and having a rotatable propeller with tiltable blades, blade tilting means operatively connected to said blades, a hollow propeller shaft attached to said propeller, a servo-motor cylinder interposed between said hollow generator shaft and said hollow propeller shaft, a piston within said servo-motor cylinder, a quantity of liquid within said cylinder, a propeller blade tilting rod extending from said piston through said hollow propeller shaft to said blade tilting means, a rotary pump mounted on said piston, the inlet and outlet of said pump being on opposite sides of said piston, a reversible electric motor mounted on the upper end of said generator shaft for rotation therewith, a telescoping drive shaft connected between the rotor of said electric motor and said pump, and means for causing the rotor of said motor to rotate in a forward or reverse direction relative to said generator shaft so as to cause said pump to raise or lower said piston. 100 105 110 115 120

3. In combination a generator having a rotatable vertical hollow shaft, a hydraulic turbine arranged below said generator and having a rotatable propeller with tiltable blades, blade tilting means operatively connected to said blades, a hollow propeller shaft attached to said propeller, a servo-motor cylinder interposed between said hollow generator shaft and said hollow propeller shaft, a piston within said servo-motor cylinder, a quantity of liquid within said cylinder, a propeller blade tilting rod extending from said piston through said hollow propeller shaft to said blade tilting means, a rotary pump mounted on said piston, the inlet and outlet of said pump being on opposite sides of said piston, a reversible electric motor mounted on the upper end of said generator shaft for rotation therewith, a telescoping drive shaft connected between the rotor of said electric motor and said pump, means for causing the rotor of said motor to rotate in a forward or reverse direction relative to said generator shaft so as to cause said pump to raise or lower said piston, and means for indicating the tilt of said propeller blades. 125 130 135 140 145

4. In combination, a hydraulic energy translating device having an adjustable blade propeller, a propeller shaft attached to said propeller, a hydraulic servo-motor cylinder carried by said propeller shaft, a piston slidable within said 150
